(21) Appl. No.: **29/120,492**

(57) **CLAIM**

(22) Filed: **Mar. 20, 2000**

The ornamental design for an egg shaped expiration date display, as shown and described.

(51) LOC (7) Cl. **19-03**

DESCRIPTION

(52) U.S. Cl. **D19/24**

(58) Field of Search **D19/20, 24, 25;**
D10/6, 15, 22, 40; 40/111; 434/238; 206/45,
9.1, 534

FIG. 1 is a perspective view of the egg shaped expiration date display showing my new design;

FIG. 2 is a front elevational view thereof;

FIG. 3 is a right side front elevational view thereof, the left side elevational view being identical thereto;

FIG. 4 is a rear elevational view thereof;

FIG. 5 is a top plan view thereof; and,

FIG. 6 is a bottom plan view thereof.

The dashed line showing of the date “Jun 30” in FIG. 1 is for illustrative purposes only and does not form a part of the invention.
